PRODUCTION OF TERTIARY OLEFINS

Filed June 26, 1940

UNITED STATES PATENT OFFICE

2,265,583

PRODUCTION OF TERTIARY OLEFINS

Donald R. Stevens, Swissvale, and William A. Gruse, Wilkinsburg, Pa., assignors to Gulf Research & Development Company, Pittsburgh, Pa., a corporation of Pennsylvania

Application June 26, 1940, Serial No. 342,584

7 Claims. (Cl. 260—677)

This invention relates to the production of tertiary olefins; and it comprises a continuous method of recovering substantially pure tertiary olefins from their mixtures with paraffins and normal and secondary olefins, such as cracking gas, wherein an extracting fluid composed essentially of a mixture of phenols and a small amount of an acid condensing agent is contacted with the hydrocarbon mixture containing the tertiary olefin at a temperature of about 20° to 80° C., thereby selectively removing the tertiary olefin from the mixture, the charged extracting fluid is separated from the residual hydrocarbon vapors and is heated to a temperature of 100° to 300° C. to release the tertiary olefin, the tertiary olefin is recovered and the extracting fluid is cooled and contacted with further quantities of the hydrocarbon mixture containing the tertiary olefin; all as more fully hereinafter described and as claimed.

Olefins such as isobutylene, trimethylethylene and the like which hydrate to form tertiary alcohols are quite reactive and commercially very useful. Thus, they can be used to alkylate phenols, forming tertiary alkyl phenols which are useful as antioxidants and as insecticides and germicides; or for alkylating isoparaffins, such as isobutane, to produce high octane gasoline. High octane gasoline can also be produced by polymerizing certain of the above described olefins, notably isobutylene, by means of heat in the presence of sulfuric acid or some other suitable agent. High molecular weight resins are also prepared by polymerizing such olefins. The present invention is concerned with the recovery of such olefins in substantially pure form and they are referred to herein and in the appended claims as "tertiary" olefins.

In the cracking of petroleum oils considerable amounts of tertiary olefins are produced in admixture with other hydrocarbons such as the paraffins and normal and secondary olefins. For example in the production of ordinary grades of gasoline it is frequent practice to remove by distillation from the condensate made in pressure cracking a highly volatile fraction which consists essentially of a mixture of four carbon hydrocarbons, butane and the butylenes, including isobutylene. This fraction is known as the "butane cut" or "C₄" cut and is an extremely volatile liquid, boiling at -10° to 6° C. at atmospheric pressure. A similar fraction known as the "pentane" or "C₅" cut which is composed of a mixture of pentane and the amylenes including tri-methyl-ethylene may also be obtained. Similar liquids are also obtainable by

"debutanizing" or "depentanizing" the gas from cracking operations which often contain liquefiable vapors.

While these petroleum cracking products composed of mixtures of hydrocarbons of the same number of carbon atoms are readily obtainable it has been found difficult to isolate the tertiary olefins from these mixtures. One method which has been proposed for this purpose is to selectively absorb isobutylene from a C₄ cut by means of 60 to 65 per cent sulfuric acid solution. This method is highly selective but is difficult to operate economically because of the polymerizing action of sulfuric acid on isobutylene.

It is an object achieved by the present invention to provide a process for the isolation of substantially pure tertiary olefins from their mixtures with other hydrocarbons of the same number of carbon atoms, without substantial polymerization; and a process which may be operated continuously and economically.

We have found that isobutylene, trimethylethylene and other tertiary olefins can be isolated in substantially pure form from their mixtures with hydrocarbons of the same number of carbon atoms, such as may be obtained in petroleum cracking operations, by contacting said mixture with an extracting fluid composed essentially of a mixture of phenols and an acid condensing agent, at a temperature of 20° to 80° C., separating the charged extracting fluid from the residual petroleum products, heating the charged extracting fluid to a temperature of 100° to 300° C., collecting the tertiary olefin gas thus liberated, cooling the extracting fluid to a temperature of 20° to 80° C., and contacting it with further quantities of the hydrocarbon mixture containing the tertiary olefin. By repeating this series of steps in a cyclic method we have been able to produce substantial quantities of tertiary olefins continuously and without excessive losses due to polymerization or side reactions.

In carrying out the method of our invention, the extracting fluid is advantageously made up from mixtures of phenols, such as phenol itself and its lower homologues such as the cresols, xylenols or ethyl phenols which are not substantially decomposed by heating to a temperature of 100° to 300° C. in the presence of an acid condensing agent. Mixtures of phenols such as the commercially available cresol mixtures and cresylic acids have proved particularly satisfactory. Substantially pure phenols, such as phenol or cresol may also be used, but the products tend to solidify and they are less desirable for the purposes of this invention.

A wide variety of acid condensing agents may be incorporated in the phenol to produce the extracting fluid. For example sulfuric acid, either alone or admixed with a mitigating agent such as a polyhydric alcohol or an alkali metal sulfate may be used, or a sulfonic acid or anhydrous aluminum chloride or a molecular compound of aluminum chloride. The exact amount of acid condensing agent used will vary with the effectiveness of the particular agent and may be regulated to control the rate at which the tertiary olefin can be taken up by the extracting fluid and to control any tendency there may be toward polymerization or side reactions at the temperature being used. In general amounts corresponding to about 0.01 to 3.0 per cent by weight of the phenolic material produce satisfactory results. Within this range when sulfuric acid is used alone it is generally advantageous to use amounts in the lower part of the range in order to avoid the tendency of sulfuric acid to cause polymerization of the tertiary olefins. If, however, a mitigating agent is used, larger amounts of sulfuric acid within this range may be used without substantial polymerization. The sulfonic acids exhibit little tendency toward polymerization or side reactions, and are highly efficient and it is generally unnecessary to use more than about 2.0 per cent for satisfactory results. Anhydrous aluminum chloride also tends to produce polymerization and side reactions and is advantageously used in the minimum effective amount, but the molecular compounds of aluminum chloride show less of this tendency and larger amounts of these compounds may be used advantageously to obtain high extraction rates.

After a suitable mixture of phenols and acid condensing agent has been prepared this extracting fluid is contacted with the hydrocarbon mixture from which the tertiary olefin is to be recovered. This contacting may be carried out by various means. In most cases we have found it advantageous to contact the hydrocarbon mixture in the vapor phase with the liquid extracting fluid for example by bubbling the vapor through the liquid or by countercurrent flow in a contact tower. The temperature during this contact should be maintained below about 80° C., advantageously about 50° to 70° C. The time of contact may be regulated by the rate of flow of the vapor and should be such that the residual vapors passing out of contact with the extracting fluid are substantially free from tertiary olefin.

The charged extracting fluid after separation from the residual vapors is heated to a temperature of about 100° to 300° C. to liberate the contained iso-olefin. This operation is advantageously effected under such conditions that the liberated iso-olefin is rapidly removed from the heating zone and from contact with the extracting fluid. This may be accomplished for example by heating the charged extracting fluid in a thin film or with rapid agitation under slight vacuum. The iso-olefin thus released is carried off and may be condensed and collected for future use or may be used directly as a reactant.

After separation and recovery of the iso-olefin, the extracting fluid is cooled to a temperature of 20° to 80° C. and is contacted with further quantities of the hydrocarbon mixture containing the iso-olefin and the series of steps above outlined is repeated. By this cyclic operation a continuous supply of iso-olefin may be obtained. The amount of polymerization and side reaction

or decomposition which takes place in each cycle is so small that the same extracting fluid may be used for relatively long periods before contamination makes its further use uneconomical.

5 In the accompanying drawing there is illustrated diagrammatically one form of apparatus suitable for carrying out the method of our invention in the continuous production of substantially pure iso-olefin. In this apparatus there is shown a contact chamber 10, which may be a packed or suitably baffled tower, provided with a temperature control means 11, such as heating or cooling jackets. Chamber 10 is provided at its bottom with an inlet 12 through which the hydrocarbon mixture from vaporizer 9 may be introduced, and at its top with an outlet containing back-pressure valve 13 through which the residual vapors may be exhausted. Holding tanks 33 and 34 are connected through pumps 10 and 18 respectively and conduit 14 with the top of chamber 10. Chamber 10 is connected at its bottom through conduit 15, pump 16 and preheater 17 with the main heating chamber 18 provided with heating coil 19. Heating chamber 18 is provided at its top with a packed tower section 20 and an outlet 21 through which the released iso-olefin is carried off. Outlet 21 is connected with a cooling coil 22 and accumulator 23 in which any phenol condensed out of the iso-olefin vapors is collected and returned to tower 20 through conduit 24. Accumulator 23 is connected through conduit 25 with an alkali scrubber 26 which in turn is connected through conduit 27, compressor 28 and conduit 29 with condenser 30 and a suitable iso-olefin collecting system (not shown).

40 The main heating chamber 18 is connected at its bottom through conduit 41 with a cooling coil 42 which in turn is connected through conduit 43 with a settling drum 44. The settling drum 44 is connected through conduit 45, pump 46 and conduit 47 with conduit 14 and the top of the contact chamber 10. An outlet 48 is provided at the bottom of settling chamber 44 through which extracting fluid may be bled off as desired for reconditioning.

45 The method of my invention may be carried out in this apparatus for example in the recovery of isobutylene from a C₄ cut using a mixture of commercial cresol containing 2.0 per cent of di-sec-butyl sulfate as the extracting fluid, as follows:

50 Cresol and di-sec-butyl sulfate in proper proportion are introduced from holding tanks 33 and 34 through pumps 35 and 36 respectively and conduit 14 into the top of chamber 10 where it flows down over the packing material or baffles as the case may be. The C₄ cut is vaporized in vaporizer 9 and is introduced into the bottom of chamber 10 through conduit 12 and passes upward through the packing or baffles where it contacts the downcoming extraction fluid. A suitable rate of flow is established so that the contact time between the liquid and vapor is such that all or most of the isobutylene in the vapors is extracted by the liquid, and the temperature is maintained below about 70° C. by introducing cooling fluid into jackets 11. The residual vapors are exhausted through back pressure valve 13.

55 60 65 70 The charged extracting fluid is pumped off through conduit 15 by pump 16 and is introduced into the preheater 17, where it is brought at least part of the way to dealkylation temperature, and passes into the main heating chamber 18 which has previously been brought to a suitable tem-

perature, usually about 200° C. by means of heating coil 19. The charged fluid may be thoroughly agitated in this chamber to facilitate rapid separation of the isobutylene.

The liberated isobutylene rises through tower 20 where entrained phenols are separated from the vapors and returned to chamber 18. The isobutylene vapor is carried out of tower 20 through conduit 21 to cooling coil 22 where it is cooled to condense out any remaining entrained cresols which are collected in accumulator 23 and returned to tower 20 through conduit 24. The isobutylene vapors are carried from accumulator 23 through conduit 25, alkali scrubber 26, conduit 27, compressor 28, conduit 29 and condenser 30 to storage.

The extracting fluid from which the isobutylene has been released passes out of chamber 18 through conduit 41 into cooling coil 42 where its temperature is reduced to a suitable temperature for introducing it into the contact chamber 10. From the cooling coil it passes through conduit 43 into settling drum 44. The cooled extracting fluid is pumped from settling drum 44 through conduit 45, pump 46 and conduit 47, and is introduced into conduit 14 through which it enters the top of contact tower 10 and is contacted with further quantities of C₄ cut vapors.

Thus a continuous flow of extracting fluid through the system is established and a continuous supply of isobutylene is obtained.

While our invention has been described herein with reference to certain specific embodiments thereof, it is to be understood that the invention is not limited to such embodiments except as hereinafter defined in the appended claims.

What we claim is:

1. A continuous process of recovering substantially pure tertiary olefins from mixtures of light petroleum hydrocarbons comprising contacting said mixture with an extracting fluid, composed essentially of a mixture of phenols and a relatively small amount of an acid condensing agent, at a temperature below about 80° C., separating the charged extracting fluid from the residual petroleum products, heating the charged extracting fluid to a temperature of 100° to 300° C., collecting the tertiary olefin gas thus liberated, cooling the extracting fluid to a temperature below about 80° C. and contacting it with a further quantity of the hydrocarbon mixture.

2. A continuous process for the recovery of a substantially pure tertiary olefin from a mixture of hydrocarbons of the same number of carbon atoms comprising contacting the hydrocarbon mixture with an extracting fluid composed essentially of a mixture of phenols and a relatively small amount of an acid condensing agent at a temperature below about 80° C. separating the charged extracting fluid from the residual hydrocarbon vapors, heating the charged extracting fluid to a temperature of 100° to 300° C., collecting the tertiary olefin gas thus liberated, cooling the extracting fluid to a temperature below about 80° C., and contacting it with further quantities of the hydrocarbon mixtures.

3. A continuous process for the recovery of substantially pure isobutylene from a butane cut of petroleum cracking hydrocarbons comprising contacting said butane cut with an extracting fluid composed essentially of a mixture of phenols

and a relatively small amount of an acid condensing agent, at a temperature below about 80° C., separating the charged extracting fluid from the residual petroleum hydrocarbons, heating the charged extracting fluid to a temperature of 100° to 300° C., collecting the isobutylene thus liberated, cooling the extracting fluid to a temperature below about 80° C. and contacting it with further quantities of the butane cut.

4. A continuous process for the recovery of substantially pure trimethylethylene from a pentane cut of petroleum cracking hydrocarbons comprising contacting said pentane cut with an extracting fluid composed essentially of a mixture of phenols and a relatively small amount of an acid condensing agent at a temperature below about 80° C., separating the charged extracting fluid from the residual petroleum hydrocarbons, heating the charged extracting fluid to a temperature of 100° to 300° C., collecting the trimethylethylene thus liberated, cooling the extracting fluid to a temperature below about 80° C. and contacting it with further quantities of the pentane cut.

5. A continuous process for the recovery of substantially pure isobutylene from a mixture of hydrocarbons of the same number of carbon atoms, comprising contacting the hydrocarbon mixture with an extracting fluid composed essentially of a mixture of cresols and a relatively small amount of an acid condensing agent at a temperature of about 50° to 70° C., separating the charged extracting fluid from the residual hydrocarbon vapors, heating the charged extracting fluid to a temperature of about 100° to 300° C., collecting the isobutylene thus liberated, cooling the extracting fluid to a temperature of about 50° to 70° C. and contacting it with further quantities of the hydrocarbon mixture.

6. A continuous process for the recovery of a substantially pure tertiary olefin from a mixture of hydrocarbons of the same number of carbon atoms comprising contacting the hydrocarbon mixture with an extracting fluid composed essentially of a mixture of phenols and 0.01 to 3.0 per cent by weight of an acid condensing agent at a temperature below about 80° C., separating the charged extracting fluid from the residual hydrocarbon vapors, heating the charged extracting fluid to a temperature of 100° to 300° C., collecting the tertiary olefin gas thus liberated, cooling the extracting fluid to a temperature below about 80° C., and contacting it with further quantities of the hydrocarbon mixture.

55 7. A continuous process for the recovery of substantially pure isobutylene from a mixture of hydrocarbons of the same number of carbon atoms, comprising contacting the hydrocarbon mixture with an extracting fluid composed essentially of a mixture of cresols and 0.01 to 3.0 per cent by weight of disec-butyl sulfate at a temperature of about 50° to 70° C., separating the charged extracting fluid from the residual hydrocarbon vapors, heating the charged extracting fluid to a temperature of about 100° to 300° C., collecting the isobutylene thus liberated, cooling the extracting fluid to a temperature of about 50° to 70° C. and contacting it with further quantities of the hydrocarbon mixture.
